UNITED STATES PATENT OFFICE.

FRANK COMAN RHEUBOTTOM, OF UNION CITY, MICHIGAN.

SPRING BED-BOTTOM.

SPECIFICATION forming part of Letters Patent No. 392,755, dated November 13, 1888.

Application filed December 20, 1887. Serial No. 258,434. (Model.)

To all whom it may concern:

Be it known that I, FRANK COMAN RHEUBOTTOM, of Union City, in the county of Branch and State of Michigan, have invented 5 a new and useful Improvement in Spring Bed-Bottoms, of which the following is a full, clear, and exact description.

This invention is in the nature of an improvement in spring bed-bottoms wherein the 10 series of springs and of parallel slats sustaining them are severally connected so as to form a united whole.

The main object of the improvement is to 15 render the bed-bottom conveniently adjustable to suit bedsteads of different sizes and to enable it to be folded into compact form for storage or transportation. An additional object is to cause the connected springs to yield readily to the expansion or contraction of the 20 bed-bottom, while always forming a continuous bearing-surface for the support of the bedding.

The invention consists in the peculiar construction and arrangement of parts, as hereininafter fully described, and pointed out in the 25 claims.

In order that my invention may be fully 30 understood, I will give a more detailed description of the construction and use of the same.

Reference is to be had to the accompanying 35 drawings, forming a part of this specification, in which similar letters of reference indicate corresponding parts in all the figures.

Figure 1 is a plan view of an adjustable 40 spring bed-bottom embodying my invention. Fig. 2 is an enlarged plan view of a portion of the same. Fig. 3 is a cross-sectional elevation on the line *x* *x*, Fig. 2, and Fig. 4 is a reduced inverted plan view of one end of the 45 bed-bottom when folded.

Upon each of the slats *A*, which are here 50 shown running lengthwise of the bed-bottom, are fixed a series of equidistant coiled springs, *B*, in any ordinary or approved manner.

The under sides of all the slats *A* are pivotally connected near either end to and by 55 lazy-tongs *C*, which allow the slats carrying the springs to be separated to any desired degree according to the size of the bedstead to which the bed-bottom is to be applied, or to be folded closely together, as shown in Fig. 4, for convenient storage or removal, while

causing the slats to always maintain their equidistant relation with each other.

In order that the springs may afford a continuous bearing-surface for the bedding whatever may be the adjustment of the bed-bottom, the upper end, *B'*, of each spring *B*, save those on the two outside slats and one-half of 60 the end springs, is passed from the under side around the upper coil, *B*², of the laterally-adjoining spring on the next adjacent slat, and then carried to and looped securely over the upper coil of the longitudinally-adjoining 65 spring on the same slat.

The order of connection is reversed on the two halves of the bed-bottom, as shown in Fig. 1, the terminal springs on opposite ends of the two halves having their upper ends 70 just outside their connection with the longitudinally-preceding springs bent inward and fastened to their own second coils. The ends of the two outside series of springs are carried around and soldered or otherwise firmly 75 attached to longitudinal stiffening-strips *E* before being looped to the respective succeeding springs.

The springs, being thus loosely connected laterally, accommodate themselves to the lateral adjustment of the slats, while being connected securely lengthwise they form always a continuous sustaining-surface.

Having thus fully described my invention, I claim as new and desire to secure by Letters 85 Patent—

1. An expandible spring bed-bottom consisting of a series of slats adjustably secured together and a series of coiled springs secured to the slats and having their upper ends 90 passed under and around the upper coil of the spring on the adjacent slat and then loosely connected to the spring on the same slat, substantially as described.

2. The herein-described expandible spring 95 bed-bottom, consisting of the longitudinal slats *A*, the lazy-tongs *C*, connecting the said slats, and the coiled springs *B*, secured to the slats and having their upper ends passed under and around the upper coil of the spring on 100 the adjacent slat, and then looped around the adjacent spring on the same slat, as specified.

FRANK COMAN RHEUBOTTOM.
